[57] CLAIM

The ornamental design for a stable cart lid, as shown and described.

DESCRIPTION

FIG. 1 is a top and rear perspective view of a stable cart lid showing my new design, the broken lines are for illustrative purpose only and form no part of the claimed design;

FIG. 2 is a top plan view thereof.

FIG. 3 is a bottom plan view thereof.

FIG. 4 is a front elevational view thereof.

FIG. 5 is a rear elevational view thereof.

FIG. 6 is a side elevational view thereof; the opposite side being a mirror image.

FIG. 7 is a cross sectional view thereof taken along the line 7—7 of FIG. 5.

FIG. 2

FIG. 3

FIG. 4
